UNITED STATES PATENT OFFICE

157,710

DRAWING INSTRUMENT

Louis A. Smitzer, Chicago, Ill.

Application May 10, 1948, Serial No. 146,263

Term of patent 3½ years

(Cl. D52—1)

To all whom it may concern:

Be it known that I, Louis A. Smitzer, a citizen of the United States, residing at Chicago, county of Cook, and State of Illinois, have invented a new, original, and ornamental Design for a Drawing Instrument, of which the following is a specification, reference being had to the accompanying drawing, forming a part thereof.

Fig. 1 is a perspective view of a drawing instrument embodying my new design;

Fig. 2 is a top plan view;

Fig. 3 is a side view;

Fig. 4 is an end view of the said drawing instrument from the mirror end;

Fig. 5 is another end view as viewed from the opposite end; and

Fig. 6 is a cross sectional view taken on line

6—6 of Fig. 2 showing the configuration of the body of the drawing instrument.

I claim:

The ornamental design for a drawing instrument, substantially as shown.

LOUIS A. SMITZER.
